[57] CLAIM

The ornamental design for an ellipsoidal vertical jet mound, as shown.

DESCRIPTION

FIG. 1 is a top plan view of an ellipsoidal vertical jet mound, showing our new design;

FIG. 2 is a side view thereof;

FIG. 3 is a side view thereof, rotated 60 degrees from the view in FIG. 2;

FIG. 4 is a top plan view thereof, the broken line showing of the spa is for illustrative purposes only and forms no part of the claimed design;

FIG. 5 is a perspective view thereof; and,

FIG. 6 is a bottom plan view thereof with the jets removed from the mound.
